UNITED STATES PATENT OFFICE.

WILLIAM A. ALEXANDER AND HARRY D. ALEXANDER, OF HUNTINGTON PARK,
CALIFORNIA.

METALLIC EDGING.

Application filed April 1, 1922. Serial No. 548,704.

To all whom it may concern:

Be it known that we, WILLIAM A. ALEXANDER and HARRY D. ALEXANDER, citizens of the United States, residing at Huntington Park, in the county of Los Angeles and State of California, have invented new and useful Improvements in Metallic Edgings, of which the following is a specification.

Our invention relates to metallic edging particularly adapted to be used around openings in building construction, such as doors or windows, and to form a stiff and durable edge therearound whereby the interior plastering on the inside of the opening and the stucco coating on the exterior wall of the building may be applied in a neat manner close to the edge of the opening, thereby forming a finished edge, thus avoiding the necessity of applying an expensive casing strip around the opening.

The above and other objects of our invention will be more fully disclosed in the following description and are illustrated in the accompanying drawings, in which:

Fig. 1 represents one corner of a window or door opening of a building showing the application of our invention thereto.

Fig. 2 is a section through the same taken on the line 2—2 of Fig. 1.

Fig. 3 is a perspective view of a fragment of our improved metallic edging.

In carrying out our invention 5 represents the frame of a window which is secured in place in the usual manner and is provided with grooves 6 on its inner and outer faces, said grooves being adapted to receive the edge 7 of one side wall 8 of the angular edging strip 9. The edging strip 9 is preferably formed of sheet metal bent at an acute angle to form the side walls 8 and 10, the edge 7 of the wall 8 being doubled over, as shown, in order to reinforce the same, and the edge of the side wall 10 being bent at approximately a right angle to the side wall 8 to form the extension 11 adapted to be spaced away from the inner and outer surfaces of the frame 5 when the strips are applied thereto. The side wall 10 is provided with a plurality of bonding openings 12 of any desired configuration for the reception of the plaster or stucco and to form a key therefor.

In applying the edging strip to the frame, the edge 7 is inserted into the groove 6, the wall lathing 13 is then inserted between the

extension 11 and the face of the frame, and both the lathing 13 and the extension 11 may be secured to the frame by means of the nails 14. After the edging strip has been applied as described, it will be obvious that the inside plastering 16 or the outside stucco material 17 may be applied in the usual manner and will become keyed to the edging strip when pressed through the openings 12 into the pocket formed between the walls 8 and 10 and the surfaces of the laths 13 and the frame 5, thus forming a durable and neat plaster finish at the corners, thereby obviating the necessity of and the expense involved in applying a casing strip around the opening. Moreover by the use of the edging strip described a very pleasing effect is produced and the plaster around the inside of the opening is protected from damage by the metallic wall 8 which may be suitably painted or decorated to conform with the finish of the wood framework.

What we claim is:

1. In combination with a grooved wall framing member, of an elongated web member, a second web member provided with bonding openings formed integral with said first named web member, said member disposed at a substantially acute angle to said first named web member, the free edge of said first named member adapted to engage the groove in the wall framing member, the second named member adapted to be secured to a wall adjacent an opening therein, whereby when the edging is secured in position, the outer face of the first named web will form a finished surface.

2. In combination with a grooved wall framing member, of a narrow elongated web member having a web provided with bonding openings formed integral with one of its longitudinally extending edges, said last named web being disposed at an angle to said first named web and having an attaching flange formed on its edge, the free edge of said first named strip adapted to be secured in the groove of the wall framing member to form a finished surface for the wall opening.

In witness that we claim the foregoing we have hereunto subscribed our names this 21st day of March, 1922.

WILLIAM A. ALEXANDER.
HARRY D. ALEXANDER.
